STEP-STOOL

Myron G. Trembly, Cleveland, Ohio

Application July 21, 1954, Serial No. 31,517

Term of patent 7 years

(Cl. D15—8)

To all whom it may concern:

Be it known that I, Myron G. Trembly, a citizen of the United States of America, residing at Cleveland, county of Cuyahoga, and State of Ohio, have invented a new, original, and ornamental Design for Step-Stool, of which the following is a specification, reference being had to the accompanying drawing, forming a part hereof.

The drawing shows a front perspective view of a step-stool embodying my new design.

I claim:

The ornamental design for a step-stool, substantially as shown.
